(57) **CLAIM**

The ornamental design for a washing machine, as shown and described.

DESCRIPTION

FIG. 1 is a front view of a washing machine in accordance with the present disclosure;

FIG. 2 is a view of the washing machine shown in FIG. 1 from the rear;

FIG. 3 is a view of the washing machine shown in FIG. 1 from the left;

FIG. 4 is a view of the washing machine shown in FIG. 1 from the right;

FIG. 5 is a view of the washing machine shown in FIG. 1 from the top;

FIG. 6 is a view of the washing machine shown in FIG. 1 from the bottom; and,

FIG. 7 is a perspective view of the washing machine shown in FIG. 1.

The broken lines shown in the drawings are for the purpose of illustrating portions of the washing machine that form no part of the claimed design.

1 Claim, 7 Drawing Sheets
